UNITED STATES PATENT OFFICE.

EDWARD G. GERMER, OF ERIE, PENNSYLVANIA.

DESIGN FOR A HEATING-STOVE.

SPECIFICATION forming part of Design No. 27,877, dated November 16, 1897.

Application filed September 27, 1897. Serial No. 653,770. Term of patent 14 years.

To all whom it may concern:

Be it known that I, EDWARD G. GERMER, a citizen of the United States, residing at the city of Erie, in the county of Erie and State of Pennsylvania, have invented a certain new and original Design for Heating-Stoves; and I do hereby declare the following to be a full, clear, and exact description of the invention, such as will enable others skilled in the art to which it appertains to make and use the same, reference being had to the accompanying drawing, and to the letters of reference marked thereon, forming part of this specification.

15 The drawing shows a perspective view of a heating-stove, showing my design.

The leading features of my design consist, substantially, in the form and ornamentation of a heating-stove embodying a base rectangular in its general contour and ornamented with raised scrollwork, a cylindrical stove-body surmounting a cylindrical fire-pot mounted on said base, ornamental open-work brackets flaring downward and outward from the lower part of the stove-body and supporting an oval rail secured to the lower extremities thereof, a front on said cylindrical stove-body ornamented with scrollwork and also having a name-plate panel thereon, and an overhanging conically-shaped stove-top having its surface ornamented with alternate bands of polished work and scrollwork and its apex surmounted by a scrollwork-ornamented urn.

35 A is the base of the stove, which is substantially rectangular in its general outline, with the corners rounded and curving gradually upward and inward to the base of the fire-pot. In the rounded corners of the base A legs B are secured, so that the upper portions thereof join with and form the corner portions of the skirting C. The front of the base A comprises an ash-box door D, provided with two projecting octagonal registers d d, which have closed fronts and operating-handles thereon. The stove-base A, the skirting C, the legs B, and the ash-box door D are covered with raised ornamental scrollwork E, with a narrow smooth band e at the top of the skirting C, extending from the sides of the door D around the sides and back of the stove-base.

F is the cylindrical body of the stove, the sides and back of which are sheet-iron, which is mounted upon the top of a cylindrical vertically-fluted fire-pot G. From the lower part of the stove-body F there is a flange f, curving outward and downward. To the upper surface of this flange f is secured the upper portions of brackets H, consisting, substantially, of central sections h, having ornamental foliate-work on the surfaces thereof and extending downward and flaring outward at their lower ends, where they join to and support a smooth oval foot-rail I. From the sides and upper part of the central portions h of the brackets H open scrollwork h' projects, so as to form an open scrollwork-screen over the upper surface of the flange f and around the greater portion of the fire-pot G.

70 The front section of the upright body F of the stove comprises the sides and top of a frame J, ornamented with raised scrollwork, a lower door K, hung in said frame and having an octagonal register k in the center thereof, of which register has a closed front and an operating-handle thereon. The surface of this door K around the register k is ornamented with raised scrollwork k'. An upper door L is also hung above the door K in the frame J, the surface of this door L being provided with a rectangular-shaped name-plate panel L', covering the greater portion of the front of said door, the remainder of the surface of said door around said name-plate panel being ornamented with raised scroll-work l.

75 M is the top of the stove, which is conical in its general contour, the lower portion thereof consisting of a smooth oval band m, which projects outward beyond and overhangs the upper portion of the stove-body F, and joining the upper edge of this band m is an oval-shaped band m', curving inward and upward, the surface of which is ornamented with raised scrollwork. To the upper edge of this band m' is joined a narrow smooth oval-shaped band m², and to the upper edge of this band m² is an oval-shaped band m³, curving inward and upward to the base n of an urn N, 100 surmounting the stove-top M, the surface of this band m³ being ornamented with raised scrollwork. The edge of the base n of the urn N is ornamented with shellwork and the

body of the urn is ornamented with scroll-work and provided with open-scrollwork handles *n'* on the sides thereof.

What I claim is—

- 5 1. In a design for a heating-stove, the design for the stove-base, substantially as shown and described.
2. In a design for a heating-stove, the design for the brackets, extending from the lower part of the stove-body downwardly and outwardly around the fire-pot, to and supporting the foot-rail, substantially as shown and described.
- 10 3. In a design for a heating-stove, the de-

sign for the front section of the stove-body, 15 substantially as shown and described.

4. In a design for a heating-stove, the design for the stove-top, substantially as shown and described.

5. The design for a heating-stove, substantially as shown and described.

In testimony whereof I affix my signature in presence of two witnesses.

EDWARD G. GERMER.
